UNITED STATES PATENT OFFICE.

GEORGE NUSSER, OF HOBOKEN, NEW JERSEY.

BUTCHER'S SAW.

SPECIFICATION forming part of Letters Patent No. 617,178, dated January 3, 1899.

Application filed September 22, 1898. Serial No. 691,596. (No model.)

To all whom it may concern:

Be it known that I, GEORGE NUSSER, a citizen of the United States, residing in Hoboken, in the county of Hudson and State of New Jersey, have invented certain new and useful Improvements in Butchers' Saws, of which the following is a specification.

This invention relates to improvements in butchers' saws by which the blade can be readily removed from the saw-frame, so as to permit the insertion of a new blade with sharp teeth whenever required, so that the saw is always in good working order; and the invention consists in the combination, in a butcher's saw, with the saw-frame having a handle and a transverse pin at its inner end and a recess in its outer end, of a saw-blade having transverse pins at its inner and outer ends, the transverse pin at the outer end engaging the recess of the saw-frame, a link provided at one end with a hook for engaging the inner pin of the saw-blade, said link being bifurcated and slotted at its opposite end, whereby said link is guided on the pin at the inner end of the saw-frame, and a cam-lever pivoted to said bifurcated end and abutting against the inner end of the saw-frame, as will be fully described hereinafter, and finally pointed out in the claim.

In the accompanying drawings, Figure 1 represents a side elevation of my improved butcher's saw. Fig. 2 is a detail side elevation of the mechanism for locking the saw-blade to the frame of the saw. Fig. 3 is a detail horizontal section on line 3-3, Fig. 2. Fig. 4 is a vertical transverse section on line 4-4, Fig. 2; and Fig. 5 is a side elevation of the locking mechanism of the blade, shown in open position for permitting the removal of the blade from the frame.

Similar letters of reference indicate corresponding parts.

Referring to the drawings, A represents the saw-frame of my improved butcher's saw; B, the handle, which is attached to one end of the saw-frame, and C the detachable saw-blade. The saw-blade C is provided with transverse pins c' c' at its ends, one of which is engaged by the outer recessed end a of the saw-frame, while the other pin c' is engaged by the hook-shaped bifurcated end h of a connecting-link, the sides D D' of the oppo-

site bifurcated end of said link passing at each side of the inner end a' of the saw-frame. The link sides D D' are each provided with a transverse slot d', by which the link is guided on the transverse pin e' at the inner end of the saw-frame. The slot and pin serve thus to retain the link on the inner end of the saw-frame and at the same time guide the link 6c lengthwise in the proper direction when tightening the saw. The link is provided with projecting portions or ears d d', to which is pivoted by the pin d' the cam-lever E between the link sides D D', and the cam-lever is provided with an eye-shaped handle e, by which the cam-lever can be taken hold of in releasing or locking the saw-blade. When the cam-lever E is moved into the position shown in Fig. 2 until it abuts against the inclined side of the inner end a' of the saw-frame, it will pull the link back and produce thereby the tight stretching and locking of the saw-blade between the outer end a of the saw-frame and the link. When the cam-lever E is moved into unlocked position, as shown in Fig. 5, the link is permitted to move forward, so that the hook portion h of the same is released from the saw-blade, so that the blade may be removed from the frame. This form of connection permits a short cam-lever, so that the whole device is compact and a full-sized saw-handle may be used through which all four fingers of the hand may be passed.

The advantages of my improved butcher's saw are that as soon as the blade becomes dull it can be taken out of the supporting-frame and a new blade with sharp teeth be inserted, so that the dull blade can be sharpened in the meantime, several blades being furnished with each saw-frame. In this way the butcher has a sharp saw available at all times without waiting for the resharpening of the blade. The locking and unlocking device is operated with great facility, so that the insertion and removal of the blade are accomplished quickly and easily and thereby a more effective saw for butchers' use obtained.

Having thus described my invention, I claim as new and desire to secure by Letters Patent—

In a butcher's saw, the combination, with a saw-frame having a handle and a transverse pin at its inner end, and a recess in its outer

end, of a saw-blade having transverse pins at its inner and outer ends, the transverse pin at the outer end engaging the recess of the saw-frame, a link provided at one end with a hook for engaging the inner pin of the saw-blade, said link being bifurcated and slotted at its opposite end whereby said link is guided on the pin at the inner end of the saw-frame, and a cam-lever pivoted to said bifurcated

end and abutting against the inner end of the saw-frame, substantially as set forth.

In testimony that I claim the foregoing as my invention I have signed my name in presence of two subscribing witnesses.

GEORGE NUSSER.

Witnesses:

PAUL GOEPEL,

M. HENRY WURTZEL.
